UNITED STATES PATENT OFFICE.

CHARLES PACK, OF ELMHURST, NEW YORK, ASSIGNOR TO DOEHLER DIE-CASTING COMPANY, A CORPORATION OF NEW YORK.

METHOD OF DIE CASTING.

Application filed November 15, 1922. Serial No. 601,076.

To all whom it may concern.

Be it known that I, CHARLES PACK, a citizen of the United States, residing at Elmhurst, in the county of Queens and 5 State of New York, have invented certain new and useful Improvements in Methods of Die Casting, of which the following is a full, clear, and exact description.

My invention relates to the art of die-casting and has particular reference to the coring of castings having one or more undercuts which prevent the withdrawal of the core. Where the undercutting is the result of the presence of a delicate or intricate design on the cored surface, the molding surface of the core must be of a sufficiently high melting point to retain its pattern accurately when the casting is poured; in other words the core must have a melting point at least substantially as high as that of the metal of the casting. This fact precludes the possibility of using a fusible core in such a case.

While this problem is frequently encountered in the practice of die-casting, a good example of its presentation is in the casting of molds for golf balls, and for that reason I have selected the casting of such molds for the explanation of my invention, it being understood, however, that my method is of general application wherever the nature of the casting requires it.

As is well known, the surface of substantially all golf balls is characterized by 35 a design formed of dimples or small depressions symmetrically and closely arranged. One of the last operations in the formation of the balls is the molding of this design in the surface, the mold consisting of two hemispherically recessed mold parts the molding surface of which has small rounded elevations complementary to the dimples in the surface of the ball. Heretofore these molds have been machined 40 out at comparatively large expense, but my method provides a way to die-cast them, thereby very materially reducing their cost.

In accordance with my invention, I first make the core of the necessary size, shape 50 and surface configuration, and with a proper die make the cast about the core. The casting with the core locked therein is then removed from the die and the inside of the core is removed in any suitable way 55 leaving only a thin and easily distortable

shell in the cavity, which can easily be withdrawn from the casting. This inside of the core may be removed by drilling or boring it out if the core is integral throughout, or if preferred the core may be made with the 60 shell separately formed and fitting over an internal filler or auxiliary core which is removable after the casting is formed.

To facilitate the distortion of the shell so as to reduce its cross sectional dimension 65 the requisite amount, I so proportion the die and core that the face of the casting about the exposed end of the core may be machined off, leaving the core protruding somewhat, and a tool is then easily applied 70 to this protruding rim after the core has been reduced to a thin shell.

My invention also comprehends other features as will appear from the following description. I shall now describe my method with the aid of the accompanying drawings in which I show apparatus suitable for one adaptation of my invention, and shall thereafter point out my invention in claims.

Fig. 1 is an elevation of a core for use 80 in die-casting a golf ball mold.

Fig. 2 is a cross section of the same on line 2—2 of Figure 1.

Fig. 3 is a section of an assembled die with the core in place.

Fig. 4 is an outside elevation of the half die carrying the core.

Fig. 5 is an elevation of the casting and core.

Fig. 6 is a section of the same after the 90 casting has been machined.

Fig. 7 is a section after the core has been reduced to a shell.

Fig. 8 is a view similar to Figure 7 showing the shell distorted and ready for withdrawal from the mold cavity.

While the core element shown in detail in Figures 1 and 2 may be formed in any suitable way, I prefer to turn it from bar stock for reasons which will hereinafter appear, and then machine the dimples in the molding surface. It may be composed of any metal suitable for the purpose, such as aluminum, aluminum alloys, brass, bronze, etc. I have found pure aluminum 100 very satisfactory since it machines easily and yet has a sufficiently high melting point to enable it to retain its surface design at the temperature to which it is subjected during the casting operation. The core, as 110

shown, has a hemispherical end 1 in which the depressions or dimples 2, are formed in any suitable way, as by machining, the diameter and surface configuration of the portion 1 being a replica of one half of a golf ball. This hemispherical end merges into a plain, cylindrical zone or band 3 of proper width, the forward limitation of which is indicated by the dotted diametral line in Figure 1. The purpose of this band will presently appear. Back of the zone 3 the diameter is reduced to form a shank or stem 4 for anchoring in the die.

The two halves of the die are shown in Figure 3, the one half 5 containing the mold cavity 6 and carrying the core, and the other half 7 containing the gate or sprue opening 8. The mold cavity 6 is shown as undercut, being of substantially frusto-conical shape. Therefore, the mold 9, as shown in Figures 5 to 8, has its side walls thicker at the top than would be the case if the top diameter were the same as the bottom diameter. Due to the pressure to which these molds are subjected in the molding of golf balls, it is desirable to provide this substantial thickness of wall throughout.

To enable the removal of the mold 9 from the die, the half 5 of the die is made in two parts, dividing on the central transverse line 5^a, as shown in Figures 3 and 4.

Any suitable metal may be used for the casting, such as a copper alloy of aluminum. I have found that, although the melting points of an aluminum core and of such an alloy are close together, the metal will not adhere to the core.

Following the casting operation, the core and casting are removed from the die, appearing at that point as shown in Figure 5. The round bosses or elevations 10 on the upper part of the surface of the concavity of the mold 9 interlock with the corresponding dimples in the core face so as to prevent the withdrawal of the core. The mold may now be mounted for machining with respect to the shank or stem 4, and since the core was originally turned, it follows that the mold may be accurately machined about the axis of the core as a center. In this operation the face of the mold surrounding the core is machined down to the diametral line of the core, which is the dotted line indicated in Figure 1, thereby reducing the mold cavity to an exact hemisphere while leaving the zone 3 of the core protruding beyond the face of the mold. This condition is shown in Figure 6.

The next step is to cut off the stem 4 and to grind out or otherwise remove the interior of the core until only a thin shell is left. This stage is shown in Figure 7. It is now a simple matter to apply a proper tool to the projecting lip 3 of the thin shell and contract the cross sectional dimension

of the outer end of the shell sufficiently to release the projections 10 on the side wall of the mold cavity from the corresponding dimples 2 in the face of the core, as shown in Figure 8, and enable the core to be withdrawn.

It is obvious that my invention is in no wise confined to the particular details of the steps as explained above, but that the details may be variously modified by those skilled in the art to adapt the method to particular conditions without departing from the spirit and scope of my invention as pointed out in the appended claims.

I claim:—

1. The method of making die-castings having an internal undercut consisting of forming a core with a unitary molding surface portion, die-casting directly upon the molding surface of the core, removing the interior of the core leaving a relatively thin integral shell, and then distorting the thin shell to reduce its cross sectional dimension sufficiently to allow withdrawal of the shell from the casting.

2. The method of making die-castings having an internal undercut consisting in forming a solid metal core with its molding surface including a portion complementary to the desired undercut, die-casting directly upon the molding surface of the core, removing the interior of the core leaving a relatively thin integral shell, and then distorting the thin shell to reduce its cross sectional dimension opposite the undercut sufficiently to allow withdrawal of the shell from the casting.

3. The method of making die-castings having an internal undercut consisting in die-casting around a suitable core, removing the face of the casting surrounding the core sufficiently to expose the end of the core somewhat, reducing the core to a thin shell, and applying a contracting force to the protruding rim of the shell sufficiently to release the shell from the casting and permit its withdrawal.

4. The method of making a die-casting having a concavity therein consisting in forming a suitable core having a supporting shank, die-casting about the core, supporting the casting from the shank of the core and machining the casting while so supported, and then separating the core and casting.

5. The method of die-casting a mold for golf balls or the like consisting in forming a hemispherical metal core having the diameter and surface configuration of the ball to be molded, die-casting the mold directly upon the said core, removing the inside of the core leaving a thin hemispherical shell, and then contracting the diameter of the edge of said shell until the shell is free to be removed from the mold.

6. The method of die-casting a mold for golf balls or the like consisting in forming a core element provided on its end with a hemispherical molding surface having the configuration of one half of the ball to be molded and continuing back from the molding surface into a substantially cylindrical extension, then die-casting the mold directly upon the core, and then removing the portion of the casting surrounding the said cylindrical extension.
7. The method of die-casting a mold for golf balls or the like consisting in forming a core element provided on its end with a hemispherical molding surface having the configuration of one half of the ball to be molded and continuing back from the molding surface into a substantially cylindrical extension, then die-casting the mold directly upon the core, then removing the portion of the casting surrounding the said cylindrical extension, then removing the inside of the core leaving a thin shell, and then applying a contracting force to the protruding rim of the shell sufficient to release the shell from the casting and permit its withdrawal.
8. The method of die-casting a mold for golf balls or the like consisting in turning from relatively soft bar metal a cylindrical core element having one end rounded to form a hemispherical molding surface with the configuration of one half of the ball to be molded and having its other end reduced to form an anchoring shank or stem, casting the mold directly upon the core, machining off the part of the casting surrounding the cylindrical portion of the core, cutting off the stem and drilling out the inside of the core leaving a thin shell, and then applying a contracting force to the protruding rim of the shell sufficient to release the shell from the casting and permit its withdrawal.

In witness whereof, I hereunto subscribe my signature.

CHARLES PACK.
